[57] CLAIM

The ornamental design for a coin entry device, substantially as shown and described.

DESCRIPTION

FIG. 1 is a front elevational view of a coin entry device, showing my new design;
FIG. 2 is a left side elevational view thereof, the right side being a mirror image thereto;
FIG. 3 is a rear elevational view thereof;
FIG. 4 is a top plan view thereof.
The broken line showing of a mounting plate in FIG. 1 is environmental only and forms no part of the claimed design.
